The ornamental design for an ornamental railroad highway crossing sign, as shown and described.

DESCRIPTION

FIG. 1 is a front elevational view of a railroad highway crossing sign showing my new design, with the pole broken in the center to indicate indeterminate length; FIG. 2 is a rear view of the sign illustrated in FIG. 1; FIG. 3 is a side view of the sign illustrated in FIG. 1; FIG. 4 is a side view of the sign illustrated in FIG. 1 opposite the side illustrated in FIG. 4;

FIG. 5 is a top view of the sign illustrated in FIG. 1; FIG. 6 is a bottom view of the sign illustrated in FIG. 1; and,

FIG. 7 is a perspective view of the sign illustrated in FIGS. 1-7.
